(57) **CLAIM**

We claim the ornamental design for a cable rail system mounting bracket, as shown and described.

DESCRIPTION

FIG. 1 is a perspective view of a cable rail system mounting bracket showing our design;

FIG. 2 is front elevational view thereof;

FIG. 3 is a rear elevational view thereof;

FIG. 4 is a left side view thereof;

FIG. 5 is a right side view thereof;

FIG. 6 is a top plan view thereof; and,

FIG. 7 is a bottom plan view thereof.

The broken lines shown in the Figures are included for the purpose of illustrating environmental features and form no part of the claimed design.
